UNITED STATES PATENT OFFICE.

GEORGE B. BOSCO, OF CHICAGO, ILLINOIS.

BRACKET FOR SHORES.

Application filed March 10, 1927. Serial No. 174,195.

The main objects of this invention are to provide improved means for securing together two crossed timbers; to provide an improved form of bracket adapted to be applied to a strut for supporting a cross piece or head; to provide improved means for securing the head against shifting relative to the strut; and to provide a bracket of this kind which is particularly adapted to be used in connection with the T-head of a shore for securing the cross piece to the upright post or strut.

An illustrative embodiment of this invention is shown in the accompanying drawing, 15 wherein:—

Figure 1 is a fragmentary side elevation of a shore to which this invention is applied, part of a mold being shown in section.

Fig. 2 is a side elevation of the same, taken from the right of Fig. 1, and partly in section for the sake of clearness.

Fig. 3 is an enlarged perspective of the bracket.

Fig. 4 is an enlarged perspective of one 25 of the braces.

The present invention may be applied to various forms of crossed timbers, but, in the construction shown, it is applied to a T-head for securing together the separate members.

30 In the form herein shown, the shore comprises an upright post or strut, on which is mounted an improved bracket which supports the cross piece. In the form shown, only one cross piece is illustrated but, if desired, several brackets may be employed for supporting any desired number of stringers one above another and on opposite sides of the strut.

As illustrated, the shore is used for supporting a mold 1 of temporary form such 40 as is used in the construction of concrete beams, joists and girders.

The shore, to which the invention is applied, comprises an upright post or strut 2 and a cross head 3, both of which are preferably timbers of standard sizes as used in construction work.

In the specific form shown, the improved bracket for supporting the head piece 3 comprises a hollow casting 4 having a substantially flat bearing plate 5 and a pair of depending side flanges 6, arranged in substantially parallel spaced relation and connected to an end flange or bearing plate 7 and an inclined bottom plate 8. With this im-

proved form of bracket, the bearing plate 5 is braced by the walls 6, 7 and 8, so as to be adapted to sustain a great amount of weight when the inner edges 9 of the walls 6 abut against the side of the post 2. 60

Formed in the end wall 7, is an aperture 10 for receiving a locking bolt 11, which extends transversely through the post 2 for securing the bracket thereto. Formed on the lower inner edge of the bracket, is a depending flange 12, which is flush with the inner edges 9 of the walls 6, and which is provided with an ear 13 for receiving a nail 14 used as additional means for securing the bracket to the strut. Formed on the inner 70 edges of the bearing surface 5 and wall 8, are prongs 15 and 16 respectively, adapted to bite into the wooden strut 2, to secure the bracket against accidental settling under the weight of a load. 75

The width of the bearing plate 5 is substantially equal to or slightly greater than the thickness of the stringer or head piece 3 which it supports. Pivotaly mounted on the bolt 11, is a latch 17, which is adapted 80 to be swung into and out of position for securing the lower end of the piece 3 from moving away from the post 2. The upper end of the timber 3 is clamped to the post 2 by a U-bolt 18, embracing the post 2 and 85 passing through apertures in the timber 3. The usual wing nuts 19 are provided for the ends of the U-bolt.

To secure the timber 3 against edgewise tilting, a pair of brace plates 20 are secured 90 to the lower edge of the timber 3 in position to engage opposite ends of the bearing plate 5 of the bracket. The braces 20 are provided with apertures 21 to receive nails or other fastening means 22 whereby they 95 are rigidly secured to the lower edge of the timber 3. Upstanding tapered ridges 23 are formed on the braces to bite into the wooden timber 3 to assist in securing the braces 20 against displacement. Formed on the inner edges of the braces 20, are depending flanges 24 adapted to abut against the ends of the bearing plate 5. 100

In operation, one or any desired number of the brackets is secured to the strut 2 in the proper position. After the stringer or cross piece 3 has been placed on the bracket, the latch 17 is swung upwardly to clamp the stringer. The wing nuts 19 may then be tightened. To remove the stringer, the wing 110

nuts 19 are loosened and the latch 17 is swung downwardly to release the grip or clamping action.

The invention being intended to be pointed out in the claims, is not to be limited to or by details of construction of any particular embodiment thereof illustrated by the drawings or hereinbefore described.

I claim:

- 10 1. In a device of the class described, a bracket comprising a substantially flat bearing plate, a pair of depending side walls on said bearing plate and arranged in substantially parallel spaced relation to each other, a depending end flange located on one side of said bracket and connecting together said walls and bearing plate, a bottom wall connecting together the lower edges of said side walls and inclined with respect to said bearing plate, a locking bolt extending through said end flange for securing said bracket to a supporting member, and a latch pivoted on said bolt and movable into position to form a stop projecting beyond said bearing plate.
- 15 2. A bracket for securing together a pair

of crossed timbers, a bearing plate adapted to be mounted on one of said timbers in position to support the other timber, a pair of brace plates adapted to be mounted on the lower edge of said other timber on respectively opposite sides of said one member in position to coact with respectively opposite sides of said bearing plate, and tapered ridges on said brace plates adapted to bite 35 into said other timber.

3. A bracket comprising a bearing plate, a pair of depending side walls on said bearing plate arranged in substantially parallel spaced relation, opposite ends of said bearing plate projecting beyond said side walls, a depending end flange connecting together said walls and plate, a locking bolt extending through said end flange for securing said bracket to a supporting member, and a 40 latch pivoted on said end flange and movable into position to form a stop projecting beyond said plate.

Signed at Chicago this 8th day of March, 1927.

GEORGE B. BOSCO.
